CLAIM

The ornamental design for a heat reduction volume compensator with curled fins for disposition between a coffee pot and hot plate, as shown and described.

DESCRIPTION

FIG. 1 is a top perspective view of a heat reduction volume compensator with curled fins for disposition between a coffee pot and hot plate showing our new design;

FIG. 2 is a top plan view thereof;

FIG. 3 is a bottom plan view thereof;

FIG. 4 is an elevational view taken along arrow 4 of FIG. 2;

FIG. 5 is an elevational view taken along arrow 5 shown in FIG. 2;

FIG. 6 is an elevational view taken along arrow 6 of FIG. 2; and,

FIG. 7 is an elevational view taken along arrow 7 of FIG. 2.
